UNITED STATES PATENT OFFICE

CHARLES S. BURSTEIN AND NATHAN SATTLER, OF NEW YORK, N. Y.

COMBINATION APRON AND MITTEN

Application filed July 2, 1930. Serial No. 465,289.

This invention relates to new and useful improvements in aprons.

The invention has for an object the provision of a device of the class mentioned which is of simple durable construction, dependable in use and efficient in action, and which can be manufactured and sold at a reasonable cost.

The invention proposes an apron having 10 shoulder straps, mitten support straps detachably mounted on said shoulder straps and extending to the lap portion of the apron, mittens on the free ends of said mitten straps, and said apron being formed 15 with slots so that said mittens may be engaged therethrough and be behind said apron and out of sight.

For further comprehension of the invention, and of the objects and advantages 20 thereof, reference will be had to the following description and accompanying drawings, and to the appended claims in which the various novel features of the invention are more particularly set forth.

In the accompanying drawing forming a material part of this disclosure:—

Fig. 1 is a front elevational view of an apron constructed according to this invention and schematically shown applied upon 30 a wearer.

Fig. 2 is a front developed view of the apron shown in Fig. 1.

Fig. 3 is a fragmentary enlarged sectional view taken on the line 3—3 of Fig. 2.

Fig. 4 is a fragmentary rear elevational view of Fig. 2, but showing the parts in another condition.

Fig. 5 is another fragmentary view similar to a portion of Fig. 2, but illustrating 40 a further modification.

Fig. 6 is a fragmentary enlarged sectional view taken on the line 6—6 of Fig. 5.

Fig. 7 is an enlarged detailed fragmentary 45 view of a portion of Fig. 5, but looking at the back of the apron.

The device comprises an apron 10 having shoulder straps 11, mitten support straps 12 detachably mounted on said shoulder straps 11 and extending to the lap portion 13 of the apron mittens 14 on the free ends of the mitten straps 12, and said apron 10 being formed with slots 15 so that said mittens 14 may be engaged therethrough and be behind said apron and out of sight. 50

The apron 10 may be of any design and construction and is shown provided with apron strings 16. The shoulder straps 11 are shown connected at their rear ends indicated by reference numeral 17. The detachable mounting of the mitten support straps 12 upon the shoulder straps is accomplished by buttons 18 secured upon the shoulder straps 11 and engaging through button-holes 19 formed in the mitten straps 12. 55

The mittens 14 may be of any conventional design and are shown to consist of a front layer 21 attached to a rear layer 22 by stitches 23 along the edges of both layers. The mitten is shown comprising a thumb portion 24 and a hand and finger portion 70 65

25. The slots 15 are shown directly above pockets 26 attached upon the front of the apron 10. A means is also provided for holding said mitten straps 12 crossed and attached to the rear of said apron for supporting purposes as illustrated in Fig. 4. This means comprises button-holes 27 75 formed in the front ends of the mittens and engageable upon buttons 28 attached upon the apron 10. 80

In the modified form of the device illustrated in Figs. 6 and 7, a means has been shown for simultaneously clamping the mittens in their positions to the rear of said apron upon lateral movements away from each other and releasing said mittens upon further lateral simultaneous movements. This means comprises flat whale-bone members 29 sewed by stitches 30 upon the rear of the apron 10 immediately in the vicinity be- 85 90

low the free ends of the mittens 14. These members 29 are spaced from each other so they are directly in line with the straps 12 extending through the slots 15. Flat springs 31 are attached at their bottom ends upon the members 29 and extend upwards and have intermediate bulged portions with the bulge arranged horizontal. Pointed rods 32 are attached upon the front edges of the mittens 14 and are engageable behind the springs 31.

The operating of the device consists in placing the mittens to the rear of the apron through the slots 15 to a position in which the mittens are located between the members 29. Then the mittens may be moved simultaneously away from each other so as to cause the pointed rods 32 to engage behind the bulged portions of the springs 31.

It is necessary that the mittens be simultaneously moved away from each other in order to properly hold the cloth of the apron so that the pointed rods engage behind the springs. For example, it is impossible to move one of the mittens laterally to cause the pointed rod 32 to engage behind the spring unless the cloth of the apron is held to prevent motion of the member 29 laterally also. But when both mittens are moved from each other against the springs, engagement of the pointed rods behind the springs is possible. Similarly, when the mittens are moved still further laterally, at the same time, the pointed rods will disengage from the springs.

A person wearing the apron may place the hands within the mittens and insert the mittens and hand through the slots 15 to a position behind the apron hid from view. Then to attach the mittens in this condition, it is merely necessary to simultaneously move the mittens laterally away from each other so that the pointed pins 32 engage behind the bulged portions of the springs 31. In that the mittens are drawn away from each other, the cloth from the apron between the members 29 is stretched and serves to hold the members 29 stationarily, while the pins 32 are engaged in place. For disengaging the mittens, the user need only reengage the hands within the mittens and continue the lateral movements of the mittens away from each other. The pins 32 then ride out from the outer sides of the springs 31 and the mittens are free for retraction out from slots 15.

The operation of the device may be followed by assuming it as shown in Fig. 1, that is, upon a wearer. The wearer may engage the hands into the mittens and lift hot pots from the stove or use the mittens for any other purposes in which need arises for protecting the hands. When the latter elements are not in use, they may be inserted through the slots 15 so as to be out of view.

If so desired, the straps 12 may be crossed behind the wearer's back and the button-holes 27 engaged upon the buttons 28 for holding the straps in the crossed position and holding the apron upon the wearer. 70

While we have shown and described the preferred embodiment of our invention, it is to be understood that we do not limit ourselves to the precise construction herein disclosed and the right is reserved to all 75 changes and modifications coming within the scope of the invention as defined in the appended claims.

Having thus described our invention, what we claim as new, and desire to secure 80 by United States Letters Patent is—

1. An apron having shoulder straps, mitten support straps detachably mounted on said shoulder straps and extending to the lap portion of the apron, mittens on the free ends of said mitten straps, and said apron being formed with slots so that said mittens 85 may be engaged therethrough and be behind said apron and out of sight.

2. An apron having shoulder straps, mitten support straps detachably mounted on said shoulder straps and extending to the lap portion of the apron, mittens on the free ends of said mitten straps, said apron being formed with slots so that said mittens 95 may be engaged therethrough and be behind said apron and out of sight, and means for holding said mitten straps crossed and attached to the rear of said apron for supporting purposes.

3. An apron having shoulder straps, mitten support straps detachably mounted on said shoulder straps and extending to the lap portion of the apron, mittens on the free ends of said mitten straps, said apron being 105 formed with slots so that said mittens may be engaged therethrough and be behind said apron and out of sight, and means for simultaneously clamping the mittens in their positions to the rear of said apron upon lateral movements away from each other and releasing said mittens upon further lateral simultaneous movements. 110

4. An apron having shoulder straps, mitten support straps detachably mounted on said shoulder straps and extending to the lap portion of the apron, mittens on the free ends of said mitten straps, said apron being formed with slots so that said mittens 120 may be engaged therethrough and be behind said apron and out of sight, and means for simultaneously clamping the mittens in their positions to the rear of said apron upon lateral movements away from each other and releasing said mittens upon further lateral simultaneous movements, comprising flat rigid members attached on the rear of the apron and spaced from each other and located in the vicinity of the free ends of the mittens when inserted through the slots, and 125 130

springs attached at their bottom ends on
said flat members and extending upwards
and having bulged intermediate portions,
and pointed rods attached upon the free
5 ends of the mittens for engagement behind
the bulged portions of the springs upon lat-
eral movement of the mittens away from
each other.

In testimony whereof we have affixed our
10 signatures.

CHARLES S. BURSTEIN.
NATHAN SATTLER.
